UNITED STATES PATENT OFFICE

2,440,501

EXCAVATING APPARATUS

Carl A. Erickson, Baltimore, Md.

Application July 27, 1945, Serial No. 607,475

12 Claims. (Cl. 214—141)

1

The invention relates to improvements in excavating apparatus.

An object of the present invention is to provide an excavating apparatus capable of rapid and economical excavation in shaft sinking operations in blasting and in the removal of the blasted material at the bottom of shafts.

A further object of the invention is to provide an excavating apparatus capable of enabling shafts to be sunk in mining and other operations in much less time and with much less labor than is possible with the manual handling or shoveling of the blasted material, whereby the cost of such excavations will be greatly reduced and the speed vastly increased.

A further object of the invention is to provide an excavating apparatus equipped with conveniently located drills for boring holes to receive blasting charges and a hinged boom carrying a pivoted excavating dipper or scoop and mounted for movement transversely of the hole or shaft and capable of enabling the excavating dipper or scoop to remove the blasted material from the entire area of the bottom of the shaft or hole and deposit the excavated material into elevating skips for hoisting the excavated material to the top of the shaft or hole.

Another object of the invention is to provide an excavating apparatus of this character adapted to be progressively lowered to excavate the shaft or hole to the required depth and provided with adjustable means for enabling it, by positively engaging opposite walls of the shaft or hole, to be securely anchored in each successive lowering operation.

Another object of the invention is to provide an excavating apparatus comprising a main frame and a carriage slidable thereon forwardly and rearwardly and carrying said transversely slidable boom, whereby the boom with its excavating dipper or scoop may be accurately positioned and progressively adjusted for complete removal of the blasted material.

A further object of the invention is to enable the carriage to be adjusted and the hinged boom and extensible section and the pivoted dipper or scoop to be actuated and controlled by cables operated by mechanism arranged on the carriage in convenient position for operation by an attendant.

With these and other objects in view, the invention consists in the novel construction, arrangement and combination of parts hereinafter fully described, illustrated in the accompanying drawings, and pointed out in the claims hereto appended, it being understood that various changes in the form, proportion, and minor details of construction may be resorted to without departing from the spirit or sacrificing any of the advantages of the invention.

2

In the drawings:

Fig. 1 is a side elevation, partly in section, of an excavating apparatus constructed in accordance with this invention and shown arranged in a shaft or hole.

Fig. 2 is a plan view of the same, partly in section.

Fig. 3 is an enlarged detail sectional view illustrating the construction of the hinged boom and the pivoted dipper or scoop and illustrating the arrangement of the cables for controlling the hinged and pivotal movements of the boom and dipper or scoop and for adjusting the extensible telescopic section of the boom.

Fig. 4 is an enlarged detail elevation illustrating the arrangement of the guides for the skips.

Fig. 5 is an enlarged detail sectional view showing one of the skips and the means for guiding the same.

Fig. 6 is a detail view of a portion of one of the sectional skip guides.

Fig. 7 is an enlarged detail sectional view of a portion of the carriage and illustrating the arrangement of the upper and lower guides for slidably mounting the carriage on the main frame.

Fig. 8 is a detail sectional view illustrating the manner of mounting the slideable bracket and sheave of the boom hoisting cable.

Fig. 9 is an enlarged detail sectional view illustrating the manner of slidably mounting the longitudinal bars of the extensible section of the main frame and also the slideable connection of the longitudinal bars with the transverse connecting bars.

Fig. 10 is an enlarged detail sectional view taken substantially on the line 10—10 of Fig. 3 and illustrating the construction of the boom, the extensible section, and the manner of mounting the upper and lower sheaves thereof.

Referring to the drawings, in which is illustrated the preferred embodiment of the invention, the excavating apparatus comprises in its construction an open main frame 1 composed of vertical bars 2 and top and bottom longitudinal and transverse connecting bars 3 and 4 and provided at the bottom with a depending framework 5 on which are mounted a plurality of pneumatic drills 6 arranged in convenient position for ready removal and use for drilling holes to receive explosive charges for blasting material at the bottom of a shaft or hole 7. The pneumatic drills are designed to be of the ordinary construction customarily employed for drilling holes for explosive charges and as any construction of pneumatic or other type of portable drill may be employed, illustration of the particular drill of this character is deemed unnecessary.

The main frame, which is connected with hoisting cables 8 to enable it to be progressively low-

ered in excavating a shaft or hole and to be removed therefrom, is substantially rectangular in plan and elevation and is provided at one end with fixed wall engaging anchoring projections 9 and at the other end with an adjustable section 10 having wall engaging anchoring projections 11. The anchoring projections 9 and 11 are arranged in pairs at the top and bottom of the main frame and the adjustable section thereof and penetrate the opposite walls of the shaft or hole and securely anchor the main frame in each adjustment thereof. While two pairs of anchoring projections are shown in each end of the main frame, any number of such projections may of course be employed.

The adjustable section of the main frame is composed of vertical bars 12, transverse connecting bars 13, and top and bottom longitudinal bars 14 to which are connected hydraulic jacks 15 arranged in pairs at the top and bottom of the main frame and adapted to thrust the anchoring projections 9 and 11 firmly into engagement with the opposite walls of the shaft or hole for anchoring the main frame.

The hydraulic jack may be supplied with fluid pressure by any suitable means for forcing the plunger portion 16 of the jack outwardly. The adjustable section 10 of the main frame is slidable thereon and it is retracted to withdraw the anchoring projections 11 from the engaged wall of the hole or shaft by means of spaced cables 17 connected at their outer ends with the slidable section of the main frame and having their inner portions connected to and arranged to be wound on drums 18 having cranks 19 or other suitable means for rotating the same for winding the cables 17 on the drums. When the anchoring projections 11 are withdrawn from the engaged wall, the anchoring projections 9 may be readily disengaged from the opposite wall and the cables 17 and drums 18 will hold the slidable section of the main frame in its retracted position while lowering the excavating apparatus from one position to another.

The main frame is provided at the top and bottom with upper and lower horizontal guides 20 and 21 arranged in pairs and located at opposite sides of the main frame and provided with grooves 22 and 23 for the reception of upper and lower rollers 24 and 25 of a carriage 26 slidable longitudinally of the main frame. The carriage consists of a framework substantially rectangular in plan and elevation and having a platform 27 and provided at the rear end with a transverse channel guide 28 which slidably receives a slide portion 29 of a bracket or hanger 30. The channel guide is provided at its open side with inwardly extending flanges 31 forming upper and lower vertical flanges 32 of the slide portion 29 of the hanger or bracket 30, whereby the hanger or bracket is slidably interlocked with the horizontal guide and is adapted to slide in the guideway thereof. Any suitable anti-friction means may of course be provided for reducing to a minimum friction incident to the hanger or bracket traversing the guide 28. The hanger or bracket carries a depending pivoted or hinged boom 33 depending from the hanger or bracket and from the carriage and connected to the hanger or bracket by a pivotal connection which may be in the form of a knuckle joint as shown and having a pivot 34.

The boom, which is constructed of suitable metal, is tubular and telescopically receives an

extension section 35 which is adjustable by the means hereinafter described to vary the effective length of the boom. The boom, which is adapted to swing forwardly and rearwardly, is provided at the lower or outer end of the extension section with a dipper or scoop 36 which is connected with said extension section 35 by a pin or pivot 37. The dipper or scoop is adapted to swing downwardly through gravity to an inclined position as illustrated in Fig. 1 of the drawings for engaging loose material at the bottom of the shaft and the boom is adapted to be swung forwardly and upwardly for carrying the dipper or scoop into engagement with the material and for elevating the dipper or scoop to a point above one or the other of a pair of elevator skips 38 which conveys the excavated material to the top of the shaft. The boom is adapted to swing downwardly and rearwardly by gravity from an elevated position to the depending vertical position illustrated in Fig. 1 of the drawings.

The dipper or scoop, which is provided at the bottom with a projecting lip 39 and which is gravity acting in one direction, is controlled by a cable 40 extending upwardly from the top of the dipper or scoop and secured at its lower end to an ear 41 of the scoop. The cable 40 extends upwardly along the boom 33 and is guided by upper and lower sheaves 42 and 43 mounted in suitable bearings 44 and 45 which may be formed integral with the tubular metal boom but the sheaves may be mounted in any other desired manner.

The cable 40 extends from the upper sheave 42 to a sheave 46 of the hanger or bracket 30 and then upwardly to an overhead pulley or sheave 47 and then to a drum 48. The drum 48, which is mounted in suitable bearings on the platform 27, is disposed transversely thereof and it may be operated by an electric motor 49 or any other suitable means. The cable 40 is wound around the drum for swinging the dipper or scoop upwardly for arranging it in proper position for scooping or dipping up the loose material at the bottom of the shaft and when it is carried into an elevated position above one of the skips 38 it is released by slackening the control cable 40, thereby permitting the scoop or dipper to swing downwardly and discharge its contents into said skip.

The boom is controlled by a hoisting cable 50 secured at its lower end to an ear 51, preferably formed integral with the extensible section of the boom and located near the lower or outer end thereof. The cable 50 extends upwardly and forwardly from the lower or outer portion of the boom to a sheave or pulley 52 mounted in a bearing bracket 53 having a slide portion 54 slidably mounted in a guide 55 disposed transversely of the front end of the carriage at a point adjacent the platform 27. The slide bearing bracket 53 which may, if desired, be provided with any suitable anti-friction devices, is arranged in alignment with the hanger or bracket 30 and is adapted to slide transversely of the carriage simultaneously with the hanger 30 when the boom is shifted laterally in either direction. The cable 50 extends rearwardly between spaced centrally arranged guide pulleys or sheaves 56 located at the front end of the platform of the carriage and it extends from the centrally arranged pulleys 56 to, and passes between, a pair of spaced guide pulleys or sheaves 57 located in advance of a transversely disposed drum 58 located in

transverse alignment with the drum 48 on which the dipper or scoop controlling cable 40 is wound. The drum 58 is actuated by an electric motor 59 or other suitable means and the cable 50 is wound around the drum 58 for swinging the boom upwardly and when the cable 50 is slackened, the boom will swing downwardly through gravity.

The hanger or bracket 30 and the bearing bracket 55 are simultaneously moved in the same direction transversely of the carriage by means of cables 60, 61, 62, and 63 arranged in pairs as clearly illustrated in Fig. 2 of the drawings. The cables 60 and 61 are secured at one end to the hanger or bracket at opposite sides thereof and they extend laterally from the hanger or bracket to pulleys or sheaves 64 and 65 located at opposite sides of the carriage. The said cables 60 and 61 then extend around the pulleys or sheaves 64 and 65 and then inwardly to spaced pulleys or sheaves 66 and 67, and then forwardly to a transversely disposed drum 68 on which the cables are reversely wound.

The other pair of cables 62 and 63 are secured to the hanger or bracket 30 at opposite sides thereof adjacent the points of attachment of the said cables 60 and 61 and they extend laterally from the hanger or bracket 30 to pulleys or sheaves 69 and 70 located at opposite sides of the carriage. They then extend forwardly longitudinally of the carriage to spaced pulleys 71 and 72 located at opposite sides of the carriage at the front portion thereof. The cables 62 and 63 then extend transversely of the carriage, crossing each other centrally thereof and passing around side pulleys or sheaves 73 and 74 and then to the bearing bracket 55 to which they are connected. The transverse drum 68 is controlled by means of an electric motor 75 and when rotated in one direction, the hanger or bracket 30 and the bearing bracket 55 are simultaneously moved in the same direction, and when the drum is rotated in the opposite direction, the direction of movement of the hanger or bracket 30 and the bearing bracket 55 is reversed.

The telescoping section 35 of the boom is moved inwardly or upwardly by means of a line or cable 76 secured at one end to an ear 77 on the inner or upper end of the boom. This line 76 extends downwardly or outwardly along the interior of the telescoping section to and around a pulley or sheave 78 mounted on the outer or lower portion of the telescoping section and it then extends upwardly or inwardly through the telescoping section and the boom to an overhead pulley or sheave 79 mounted on the main frame. A line or cable 80 is secured to the upper end of the telescoping section at 81 and extends downwardly or outwardly to and around the lower pulley 82 and then upwardly through the telescoping section and the boom to an overhead pulley or sheave 83. The cables or lines 76 and 80 extend from the overhead pulleys 79 and 83 to a drum 84 and are reversely wound around the same so that when the drum is rotated, one of the lines or cables will be wound on the drum and the other unwound therefrom.

The telescoping section 35 with the pivoted dipper has sufficient weight to move downwardly or outwardly by gravity action and this arrangement of the lines or cables 76 and 80 affords better control of the telescoping section than a single line or cable. The drum is mounted on the platform 27 and is actuated by an electric motor 85 or other suitable means.

The carriage is moved forwardly and rear-

wardly along the main frame by means of cables or lines 86 and 87 extending longitudinally of the main frame from an intermediate point on the carriage to the front and rear ends of the main frame. The cable or line 86 is secured at its outer or front end at 88 to the extensible section of the main frame and the other cable or line 87 is secured at its outer or rear end at 89 to the rear end of the main frame. The inner portions of the cables 86 and 87 are reversely wound around a drum 90 so that when the drum is rotated one of the cables will be wound around the drum 90 and the other cable unwound therefrom and the carriage moved longitudinally of the main frame. The drum 90 which is mounted on the platform 27 of the carriage is actuated by an electric motor 91 or other suitable means.

The skips 38, which are alternately raised and lowered by hoisting cables 92 to convey the excavated material to the surface of the ground and to return the empty skips to the bottom of the hole, are provided at the back and sides with short vertical slides 93 and 94 having outer flanged webs providing portions substantially T-shaped in cross section to slide in and interlock with rear and side channel guides 95 and 96. The rear and side channel guides have spaced transverse flanges 97 and 98 forming slots which receive the web portions of the slides 93 and 94 of the skips 38. Any other suitable form of slides and guides may be provided for guiding the skips 38 in their vertical movement.

As the hole deepens, it is designed to be timbered as shown at 99 but the walls may be coated or walled with cement or any other suitable material to provide a lining for the hole and prevent caving in of the walls thereof. The guides for the skips are designed to be constructed of sections and to be extended as the hole deepens. The adjacent ends of the sections of the guides may be connected by suitable joints such as are illustrated at 100 in Fig. 6 of the drawings. The sections of the guides are designed to be supported by the timbered portion of the hole and also by the framework of the main frame and when moving the apparatus from a hole, sections of the guides may be pinned to adjacent timbers as illustrated at 101 in Fig. 6 of the drawings.

The boom 33 is rectangular in cross section and the extensible section, which may be constructed in any desired manner, is preferably composed of spaced parallel side bars or members 102 and 103 which are connected together at their upper and lower terminals and which slidably fit the interior of the boom. The upper pulley 78, around which the cable 76 passes, is mounted on the side bar or member 102 within a bearing bracket 104 and when the cable 76 is wound around its drum, the telescoping section will be moved upwardly or inwardly.

The lower pulley 82, around which the cable 80 passes, is carried by the boom and is located adjacent the other side bar or member 103 of the telescoping section. The boom is provided with bearing brackets 105 in which the lower pulley 82 is mounted. The bearing brackets are secured to the boom at opposite sides thereof and when the cable 80 is wound around its drum, the telescoping section will be positively moved downwardly and outwardly.

In order to enable the longitudinal bars of the extensible section of the main frame to be adjusted independently of each other to position them properly to engage the irregular surface of a hole, the longitudinal bars 14 are slidably con-

nected with the transverse bars 13 and are provided with guides or ways 106 in which slide approximately T-shaped terminal portions 107 of the transverse bars, whereby the transverse bars and the longitudinal bars are slidably interlocked with each other. Any suitable means, such as a clamping screw 108, may be provided for rigidly securing the longitudinal bars in any adjusted position to suit the character of the surface to be engaged by the projections 11.

What is claimed is:

1. An excavating machine including a main frame provided at opposite sides with longitudinal ways and having means for engaging walls of an excavated hole for securing the main frame in different positions in said hole, hoisting means connected with the main frame for lowering it into said hole as the excavation of the same progresses and for removing it from the hole when the excavation thereof is completed, a carriage slidable in the ways of the main frame and provided with a transverse guide, a pivoted boom mounted for sliding movement back and forth along said transverse guide and provided with an extensible section, a dipper pivotally mounted on the extensible section of the boom at the outer end thereof, means for actuating and controlling the boom to swing the same and to slide the boom along said transverse guide, means for effecting adjustment of said extensible section to vary the effective length of the boom, and a dipper line connected with the dipper and guided on and carried by the boom in the sliding movement thereof.

2. An excavating machine including a main frame provided at one end with fixed projections for engaging a wall of an excavated hole and having at the other end an extensible section slidably mounted on the main frame and provided with projecting means for engaging the opposite wall of said hole, hydraulic jacks mounted on the main frame and connected with the extensible section for moving the same outwardly to engage said projections with said walls of the hole for adjustably securing the main frame in position for excavating, excavating means carried by and depending from the main frame for excavating the hole below the main frame, drums having lines wound thereon and connected with the extensible section, and means for rotating the drums for moving the extensible section inwardly.

3. An excavating machine including a main frame provided at opposite sides with longitudinal ways and having means for engaging walls of an excavated hole for adjustably securing the main frame in said hole, a carriage slidably mounted in the ways of the main frame and provided with front and rear transverse guides, front and rear brackets slidable in said guides, a boom pivoted to the rear bracket and depending therefrom, a dipper carried by the boom, a cable connected with the boom and guided on the front bracket for swinging the boom, and means mounted on the carriage and connected with the front and rear brackets for simultaneously sliding the same in the same direction along the transverse guides.

4. An excavating machine including a main frame provided at opposite sides with longitudinal ways and having means for engaging walls of an excavated hole for adjustably securing the main frame in said hole, a carriage slidably mounted in the ways of the main frame and provided with front and rear transverse guides, front

and rear brackets slidable in said guides, a boom pivoted to the rear bracket and depending therefrom, a pivoted dipper carried by the boom, a cable connected with the boom and guided on the front bracket for swinging the boom, means mounted on the carriage and connected with the front and rear brackets for simultaneously sliding the same in the same direction along the transverse guides, and a dipper line connected to and controlling the pivoted dipper and extending along and guided by the boom and the rear bracket.

5. An excavating machine including a main frame, means for adjustably positioning the main frame in an excavated hole, excavating mechanism carried by the main frame and including a pivoted boom having a pivoted dipper, operating means connected with the boom and the dipper for swinging the boom and for permitting the dipper to discharge its contents, skips movable vertically through the main frame for conveying excavated material to the surface of the ground and adapted to receive excavated material from the dipper when at the lower limit of their vertical movement, said skips being provided with vertical slides and extensible vertical sectional guides receiving the slides and extending from the top to the bottom of the hole, sections of the guides being mounted on the main frame, and hoisting cables connected with the skips for raising and lowering the same.

6. An excavating machine including a main frame, means for adjustably positioning the main frame in an excavated hole, excavating mechanism carried by the main frame and including a pivoted boom having a pivoted dipper, operating means connected with the boom and the dipper for swinging the boom and for permitting the dipper to discharge its contents, skips movable vertically through the main frame for conveying excavated material to the surface of the ground, said skips being provided at the sides and rear with vertical slides, extensible vertical sectional guides receiving said slides and extending from the top to the bottom of the hole, and hoisting cables connected with the skips for raising and lowering the same.

7. An excavating machine including a main frame provided with longitudinal ways, a carriage slidably mounted in said ways and provided with front and rear transverse guides, front and rear brackets slidable in a transverse guide, a boom pivoted to and depending from the rear bracket, a dipper carried by said boom, a cable connected with the boom for swinging the boom upwardly, said cable extending to and guided on the front bracket and movable with the same when the front bracket slides along the front guide, a drum mounted on the carriage, cables reversely wound around the drum and connected with the rear bracket and extending laterally in opposite directions therefrom, means for guiding said cables to said drum, front cables connected with and extending laterally from the front bracket and crossed intermediate of their ends and extending to opposite sides of the rear portion of the carriage and laterally therefrom to the rear bracket and connected therewith, and means for guiding the cables which are connected with the front bracket, said drums when rotated being adapted to move the front and rear brackets simultaneously in the same direction.

8. An excavating machine including a main frame provided with longitudinal ways, a carriage slidably mounted in said ways and provided with

front and rear transverse guides, front and rear brackets slideable in a transverse guide, a boom pivoted to and depending from the rear bracket, a dipper carried by said boom, a cable connected with the boom for swinging the boom upwardly, said cable extending to and guided on the front bracket and movable with the same when the front bracket slides along the front guide, a drum mounted on the carriage, cables reversely wound around the drum and connected with the rear bracket and extending laterally in opposite directions therefrom, means for guiding said cables to said drum, front cables connected with and extending laterally from the front bracket and crossed intermediate of their ends and extending to opposite sides of the rear portion of the carriage and laterally therefrom to the rear bracket and connected therewith, means for guiding the cables which are connected with the front bracket, said drum when rotated being adapted to move the front and rear brackets simultaneously in the same direction, hoisting cables connected with the main frame, and means for adjustably positioning the main frame in an excavated hole.

9. An excavating machine including a main frame of approximately the size of the hole to be excavated provided at opposite sides with ways and having means for engaging walls of an excavated hole for securing the main frame in different positions in said hole, hoisting means connected with the main frame for lowering it into the hole as the excavation of the same progresses and for removing the main frame from the hole when the excavation thereof is completed, a carriage slideable in the ways of the main frame and extending across the same and provided with two separate spaced guiding means extending transversely of the carriage, a pivoted boom mounted for movement along one of said transverse guiding means, a dipper carried by said boom and means mounted for sliding movement in the other of said guiding means and connected with the boom controlling the pivotal movement thereof.

10. An excavating machine including a main frame of approximately the size of the hole to be excavated provided at opposite sides with ways and having means for engaging walls of an excavated hole for securing the main frame in different positions in said hole, hoisting means connected with the main frame for lowering it into the hole as the excavation of the same progresses and for removing the main frame from the hole when the excavation thereof is completed, a carriage slideable in the ways of the main frame and extending across the same and provided with two separate spaced guiding means extending transversely of the carriage, a pivoted boom mounted for movement along one of said transverse guiding means, a dipper pivotally mounted in the boom at the outer end thereof, means mounted for sliding movement in the other of said transverse guiding means and connected with the boom for controlling the pivotal movement thereof, and separate means connected with the dipper and extending along the boom and carried with the same in the sliding movement thereof.

11. An excavating machine including a main frame of approximately the size of the hole to be excavated provided at opposite sides with ways

and having means for engaging walls of an excavated hole for securing the main frame in different positions in said hole, hoisting means connected with the main frame for lowering it into the hole as the excavation of the same progresses and for removing the main frame from the hole when the excavation thereof is completed, a carriage slideable in the ways of the main frame and extending across the same and provided with front and rear guiding means extending transversely of the carriage, a pivoted boom mounted for sliding movement in the rear guiding means and provided with an extensible section, a dipper carried by the extensible section of the boom, means mounted in the front guiding means for sliding movement transversely of the carriage and connected with the boom for controlling the pivotal movement thereof, and means connected with the extensible section of the boom and extending along the boom and carried by the same in its sliding movement and connected with the extensible section for effecting adjustment of the extensible section to vary the effective length of the boom.

12. An excavating machine including a main frame of approximately the size of the hole to be excavated provided at opposite sides with ways and having means for engaging walls of an excavated hole for securing the main frame in different positions in said hole, hoisting means connected with the main frame for lowering it into the hole as the excavation of the same progresses and for removing the main frame from the hole when the excavation thereof is completed, a carriage extending across the main frame and slidably mounted in the ways thereof and provided with front and rear transverse guiding means, a bracket slidably mounted in the rear guiding means for movement back and forth in said guiding means, a boom pivoted to and depending from the bracket, a dipper pivoted to the outer end of the boom, means mounted in the front guiding means for sliding movement transversely of the carriage and connected with the boom for controlling the pivotal movement thereof and separate means connected with the dipper and extending along the boom and carried by the same in the sliding movement thereof for controlling the pivotal movement of the dipper.
